UNITED STATES PATENT OFFICE.

GARRETT WHITE, OF CHAPEL HILL, TENNESSEE, ASSIGNOR OF ONE-HALF TO WILLIAM B. NEELY, OF CHAPEL HILL, TENNESSEE.

INVALID-LIFTING APPARATUS.

977,243.

Specification of Letters Patent. Patented Nov. 29, 1910.

Application filed July 23, 1910. Serial No. 573,544.

To all whom it may concern:

Be it known that I, GARRETT WHITE, a citizen of the United States of America, and a resident of Chapel Hill, Marshall county, in the State of Tennessee, have invented a new and useful Improvement in Invalid-Lifting Apparatus, of which the following is a specification.

This invention relates to those mechanical devices for handling or moving invalids, especially patients in hospitals, known as lifting apparatus.

The present invention consists in certain novel combinations of parts which are or may be embodied as a whole in an invalid lifting apparatus of peculiar construction, and in each of such combinations of parts, as hereinafter particularly described and claimed.

Such apparatus is designed to lift and carry an invalid with less assistance than and quite as comfortably as the ordinary wheeled stretchers employed in hospitals; and to obviate the necessity of transferring the patient by hand from bed to stretcher, from stretcher to operating table and so forth; and the parts of the apparatus should be easily sterilizable.

The leading objects of the present invention are to render a full-length windlass free ended and substantially balanced in a single midlength support, and to provide for the manipulation of the windlass from one end thereof by a single attendant; to permit such windlass to be moved bodily toward or away from a single main upright or vertical post, or to be turned into a vertical position when not in use; to permit such windlass to turn around the vertical axis of said midlength support without turning the base; and to render said support normally fastened against such movement.

Other objects will be set forth in the general description which follows:

Two sheets of drawings accompany this specification as parts thereof.

Figures 1 and 2 are perspective views showing two species of the improved apparatus; Figs. 3, 4, 5, 6, 7 and 8 are detail views of parts hereinafter specified common to both species; Figs. 9 and 10 are sectional detail views showing a feature of construction common to both species but conveniently omitted from Fig. 2; Figs. 11, 12, 13, 14 and 15 are detail views of other parts

represented in Fig. 1; Figs. 16 and 17 are detail views of a brace which is intended to be common to both species, but is conveniently omitted from Fig. 1; and Figs. 18, 19 and 20 are detail views showing features of construction represented in Fig. 2.

Like reference characters refer to like parts in all the figures.

A vertical post, 1, and a horizontal base frame, 2, are constructed of iron pipe with cast coupling pieces rigidly uniting the several pipe lengths; rigid braces, 3, adapted to keep the post 1 perpendicular to the base frame 2, unite them; and the base frame 2 is supported by casters, 4, swiveled in said coupling pieces, and having the customary rubber-tired wheels of suitable size.

A rigid right-angled cast coupling piece, 5, at the top of the post 1, admits one end of a horizontal frame member, 6, of iron pipe, preferably so as to provide for endwise and angular adjustment, and the other end of said horizontal member 6 is provided with a tightly attached and rigid right-angled coupling piece, 7. The vertical bore of the latter is occupied by the shank of a depending L-shaped windlass support, 8, having a head, 9, at its upper end adapted to resist endwise displacement, and a horizontal sleeveportion, 10, in which a free-ended and full length windlass, 11, formed by another piece of pipe, has a midlength bearing, and is substantially balanced; being of sufficient strength and rigidity to permit the suspension of a human patient therefrom in horizontal position and lengthwise with reference to the windlass, as represented in Fig. 1 or Fig. 2.

A hand-wheel, 12, Figs. 1-5, fast on one end of the windlass 11, and preferably composed of a metallic hub-and-spoke casting and a wooden rim, provides for turning the windlass on its axis by hand; and the windlass is preferably provided with a sufficient number of spools, 13, as means for locating or distributing the patient suspending devices.

A brace, 14, Figs. 2, 16 and 17, hinged to a collar, 15, fast on the post 1, provides for steadyng the wheel end of the windlass during the lifting operation, as in Fig. 2, after which the bifurcated free end of the brace, shown at *a* in Figs. 16 and 17, may be disengaged from the windlass, and the brace permitted to hang at the side of the post 1.

The patient suspending means common to the two species include flexible straps, 16 or 16' and 16'', of leather or webbing, which are attached at their upper ends to the windlass 11 by suitable means, such as staples, 17, Fig. 19, extending through the windlass and securely fastened; the straps winding upon or between the spools 13 as preferred.

Other devices common to the two species 10 include fastening means preferably in the shape of a vertical set screw, 18, Figs. 1, 2 and 8, whereby the horizontal frame member 6 is rendered normally immovable with reference to the post 1 and base frame 2. 15 By loosening the frame member 6 at 18 the windlass support 8 may be moved toward or away from the post 1, or the windlass may be turned parallel with the post 1 when the apparatus is not in use.

20 Another device, intended as aforesaid to be common to both species, consists of a spring bolt, 19, Figs. 1, 9 and 10, the housing of which is fixedly attached to the top of the coupling piece 7, and which interacts 25 with radial sockets, 20, in the head 9 of the windlass support 8 to fasten the latter and therewith the windlass and its load in different angular positions with reference to the post 1 and base-frame 2. One position 30 in which the windlass 11 may thus be fastened may be in contact with the post 1, and it may preferably be further secured in this position, while moving the apparatus as a whole from place to place by means of a 35 strap, 21, Fig. 2, attached to the post.

Another part of the invention common to both species consists of means for rendering the windlass 11 self-fastening as it is turned to lift an invalid, and for freeing it during 40 the operation of lowering the invalid under the control of the hand-wheel 12. Suitable means for these purposes include a longitudinally movable rod, 22, Figs. 3-7, within the wheel end of the windlass, carrying a 45 dog, 23, which protrudes through longitudinal slots, 24, in the windlass, and interacts with crown ratchet teeth, 25, on one end of said sleeve portion 10 of the windlass support 8; a spring, 26, holding said dog normally in mesh, and a thumb lever, 27, providing for the easy manipulation of the device by one of the hands of the attendant 50 who has charge of the wheel 12.

In the first species, represented primarily 55 by Fig. 1, the suspending straps 16 are only two in number and engage at their lower ends horizontal wrist pins, 28, and 29, rigidly attached respectively to a head piece, 30, shown detached by Figs. 12 and 13, and 60 at a corresponding point to a cross piece, 31, on a foot piece, 32, shown detached by Figs. 14 and 15. These pieces 30 and 32 are of metal and fixedly attached at their lower ends to the ends of a rectangular metallic 65 frame, 33, the side pieces of which are of

angle iron as shown in cross-section in Fig. 11, and provided with depending staples, 34. A sufficient number of cross-pieces, 35, Figs. 1 and 11, in the form of polished pieces of flat metal, complete the device. Each of 70 these is constructed with a holding end, 36, Fig. 11, formed by two rectangular bends, to interact with either of the side pieces of the frame 33, and prevent displacement, and a flat end, 37, which protrudes through one 75 of the staples 34 at an opposite point. The upper portion of the foot piece 32 forms a rigid slotted guide, 38, Figs. 1, 14 and 15, through which the foot end of the windlass 11 protrudes so that the invalid supporting 80 frame 33 is guided or steadied in its approach to the windlass in the lifting operation.

In the second species, as represented by Figs. 2 and 18, the lower ends of the main 85 suspending straps 16', each of which is double, are attached by rigid buckle-forming pieces 39, Fig. 18, to U-shaped carriers, 40, at one end of each; these carriers being adapted to have their free ends, 41, Fig. 18, 90 inserted endwise beneath the patient. Such carriers may be constructed wholly of polished metal to facilitate sterilizing them, or they may be padded, as preferred. The head strap 16'' forms a loop at its lower end to 95 embrace the head of the patient.

Other like modifications of the improved lifting apparatus will suggest themselves to those skilled in the art.

Having thus described said improvement, I claim as my invention, and desire to patent under this specification:

1. An invalid lifting apparatus having, in combination, a movable base frame, a vertical post rigidly supported by said frame, a horizontal frame member rigidly supported at one end by the upper end of said post, a depending windlass support located at the other end of said horizontal member and having a subjacent horizontal bore, a free-ended and full length horizontal windlass having a midlength bearing in said bore and substantially balanced therein, means for suspending a patient from said windlass and beneath the same in a horizontal position, and means for manipulating said windlass from one end thereof.

2. The combination with an invalid lifting windlass of a movable base frame, a vertical post rigidly supported by said frame, a right-angled coupling piece at the upper end of said post having a horizontal bore, a horizontal frame member supported at one end by said coupling piece and movable in said bore, a depending windlass support attached to the other end of said frame member, and means for fastening and unfastening said frame member arranged to interact with said coupling piece.

3. The combination with an invalid lift-

130

ing windlass of a movable base frame, a vertical post rigidly supported by said frame, a right-angled coupling piece at the upper end of said post having a horizontal bore, a horizontal frame member supported at one end by said coupling piece and movable in said bore, a depending windlass support attached to the other end of said frame member, and a set screw interacting with said coupling piece to render said frame member normally fastened and to provide for unfastening it.

4. The combination, in an invalid lifting apparatus, of a movable base frame, a vertical post rigidly supported by said frame, a horizontal frame member rigidly supported at one end by the upper end of said post, a right-angled coupling piece fast on the other end of said frame member and having a vertical bore, a windlass support having a vertical member rotatable in said bore and having a displacement-preventing head at its upper end and a subjacent horizontal sleeve portion, and a free-ended horizontal windlass having a midlength bearing in said sleeve portion.

5. The combination, in an invalid lifting apparatus, of a movable base frame, a vertical post rigidly supported by said frame, a horizontal frame member rigidly supported at one end by the upper end of said post, a right-angled coupling piece fast on the other end of said frame member, a depending L-shaped windlass support rotatable in the vertical bore of said coupling piece and having a head at its upper end constructed with radial sockets, a spring bolt the housing of which is attached to said coupling piece and which interacts with said sockets, and a horizontal windlass having a midlength bearing in a sleeve portion of said windlass support.

6. The combination, in an invalid lifting apparatus, of a movable base frame, a vertical post rigidly supported by said base frame, a horizontal frame member rigidly supported at one end by the upper end of said post, a depending windlass support located at the other end of said horizontal member and constructed with crown ratchet teeth at one end of a horizontal sleeve portion, a horizontal windlass of metallic pipe having a midlength bearing in said sleeve portion and provided with longitudinal slots adjacent to said ratchet teeth, a hand wheel fast on one end of said windlass, a longitudinally movable rod within the wheel end of the windlass, a dog carried by said rod and protruding through said slots to interact with said ratchet teeth, a spring which normally keeps said dog in mesh, and a thumb lever carried by said wheel and adapted to be moved by one of the hands grasping said wheel to free the windlass by retracting said dog.

65 7. The combination, in an invalid lifting

apparatus, of a movable base frame, a vertical post rigidly supported by said base frame, a horizontal frame member rigidly supported at one end by the upper end of said post, a depending windlass support located at the other end of said horizontal member, a horizontal windlass having a midlength bearing in said support, and means for suspending a patient from said windlass including straps attached thereto at their upper ends, head and foot pieces provided with rigid wrist pins to interact with the lower ends of said straps, a rectangular frame to which said head and foot pieces are attached, and movable cross pieces insertible endwise beneath the patient and adapted to be supported by said rectangular frame.

10 8. The combination in an invalid lifting apparatus, of a movable base frame, a vertical post rigidly supported by said base frame, a horizontal frame member rigidly supported at one end by the upper end of said post, a depending windlass support located at the other end of said horizontal member, a horizontal windlass having a mid-

length bearing in said support, and means for suspending a patient from said windlass including straps attached thereto at their upper ends, head and foot pieces provided with rigid wrist pins to interact with the lower ends of said straps, a rectangular frame to which said head and foot pieces are attached and which is constructed with side pieces of angle iron, and movable cross pieces insertible endwise beneath the patient and each constructed with a holding end formed by two rectangular bends, and adapted to interlock with one of said side pieces.

9. The combination, in an invalid lifting apparatus, of a movable base frame, a vertical post rigidly supported by said base frame, a horizontal frame member rigidly supported at one end by the upper end of said post, a depending windlass support located at the other end of said horizontal member, a horizontal windlass having a midlength bearing in said support, and means for suspending a patient from said windlass including straps attached thereto at their upper ends, head and foot pieces provided with rigid wrist pins to interact with the lower ends of said straps, a rectangular frame to which said head and foot pieces are attached and which is constructed with side pieces of angle iron and staples depending therefrom, and movable cross pieces insertible endwise beneath the patient each constructed with a holding end adapted to interlock with either of said side pieces and with a flat end adapted to engage one of the staples on the other side piece, substantially as hereinbefore specified.
